UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,810, dated March 14, 1882.

Application filed February 11, 1882. Term of patent 3½ years.

To all whom it may concern:

Be it known that I, WINTHROP L. JACOBS, of East Orange, in the county of Essex and State of New Jersey, have invented a new and useful Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group consisting of the four-leaved flower *a*, with projecting bud, the flower and leaf figures *b* and *c*, and the angular connecting-stems with projecting blossoms.

The group B is shown in part on one side and in part on the other side of the design. It consists of the rectangular flower figure *d*, the flower and leaf figure *e*, and the flower figure *f*, all connected by angular stems bearing at their junction a circular flower.

C is a group consisting of a star-like figure, from which project three angular broken stems bearing two of them a leaf-like flower figure, and the third a circular flower.

The group D consists of the figures *g* *h* *k* and the connecting broken angular branch bearing circular flowers and bud-like figures at its angles and in projecting branches. *g* is a figure having a circular flower at its base, above four laterally-projecting leaves with tendrils, and at the apex a triple-pointed flower with tendrils. *h* has the appearance of a flower with a double calix and a pointed bulb above with tendrils. *k* resembles a flower with a fan-like center, three leaves on each side, and a pointed bud-like apex.

The group E consists of the figures *l* and *m* and an angular stem on which they are set, which also bears a circular and a conical flower and bud. *l* is similar to *g* of group D. *m* is a rectangular flower-figure with a circular flower in the center and projecting tendrils.

The group F consists of a circular star-like flower with a projecting tendril and two short stems, bearing the one a five-leaved figure and the other a small circular flower.

The group G consists of the four-petaled flower *n*, from which spring three right-lined angular branches bearing buds and tendrils and the fig-

ures *o* and *p*. *o* is similar to *g* of group D. *p* is somewhat similar to *k* of group D.

The group H consists of an open flower figure with tendrils, and having a branch projecting from it bearing on one fork a circular and on the other a conical flower figure.

The group K consists of a star-shaped figure and a connected broken angular stem bearing at different parts of its length a three-leaved and a five-leaved figure and several small circular and conical flower figures.

The group L consists of a central circular flower figure, above it a five-leaved and below it two three-leaved figures, and arranged around several smaller flower figures and the connecting angular stem and its branches.

The group M consists of the figures *q* *r*, a connecting angular stem and its branches and tendrils, and connected smaller flowers. *q* is a full-blown flower with a circular center. *r* is a conical flower figure somewhat similar to *b* of group A.

The group N consists of a circular and a spreading flower figure and three smaller flower figures, two cross-like and one conical, all arranged on a short angular stem. The group is shown in part on one side and in part on the other side of the design.

The group O consists of the figures *s* *t* *u* *v*, two small circular flowers, and the angular connecting-stems and projecting tendrils. It is shown in part on each side of the design. *s* is a large circular serrated flower figure. *t* is a conical five-leaved figure with a circular flower at its base and projecting tendrils. *u* is a conical seven-leaved figure with a circular flower at its base and projecting tendrils. *v* is similar to the star-shaped central figure of group C.

The group P consists of the figures *w*, *x*, and *y*, and the connecting angular stem and branches, and its projecting tendrils and smaller leaf and flower figures. *w* is a rectangular figure with a circular center. *x* is somewhat similar to *k*. *y* is a bulb-shaped figure and occurs twice in this group.

These groups traverse a field, *z*, ornamented by small circular figures with rectangular star-centers, and having various minor groups filling in the spaces between the larger groups enumerated, as shown in the photograph.

The design derives much of its peculiar character, as a whole, from the angular character of the short right-lined stems connecting different parts of the same group.

5 I claim—

1. The design for carpets, consisting, of the groups A, (including *a b c*.) B, (including *d e f*.) C, D, (including *g h k*.) E, (including *l m*.) F, G, (consisting of *n o p*.) H, K, L, M, (including *q r*.) N, O, (including *s u t v*.) and P, (including *w x y*.) with connecting angular stems, substantially as shown.

2. The design for carpets, consisting of the groups A, (including *a b c*.) B, (including *d e f*.) C, D, (including *g h k*.) E, (including *l m*.) F, G, (consisting of *n o p*.) H, K, L, M, (including *q r*.) N, O, (including *s u t v*.) and P, (including *w x y*.) with connecting angular stems, and the field *z*, substantially as shown.

WINTHROP L. JACOBS.
